ELECTRIC LAMP HOLDER

Charles Henri Joseph Anderson and Johannes Hendricus Franciscus van Werd, Eindhoven, Netherlands, assignors to Hartford National Bank and Trust Company, Hartford, Conn., as trustee

Application August 2, 1950, Serial No. 177,261

Claims priority, application Netherlands
August 11, 1949

4 Claims. (Cl. 200—51.07)

1

This invention relates to holders for fastening tubular electric lamps, more particularly low-pressure mercury-vapour discharge tubes, the holder consisting of a housing and a member rotatably mounted therein and adapted to switch the current to the lamp on or off on being turned.

With a known holder of this type, the rotatable member comprises at least two movable contacts which are intended to make contact with the same number of contacts of the lamp cap and are also adapted to engage with the same number of fixed contacts in the housing, in accordance with the position into which the member is moved.

A limitation of such lamp holders is that an unsatisfactory contact is established between the movable contacts and the contacts of the lamp cap, if the two holders, between which the tubular lamp is usually secured, are not correctly spaced apart from one another.

A further limitation is that the lamp and the member can only be turned freely if the axis of the member and of the lamp coincide comparatively accurately. A frequent error made in inserting lamps into such holders is that the lamp is inserted into a holder only at one end and then turned. Again, it often occurs that the holder is not secured in the correct direction. Then the said axes do not coincide, which may involve jamming of the movable parts or rupture.

The invention has inter alia for its object to mitigate these limitations or to obviate them completely.

According to the invention, the rotatable member is movable in the direction of the axis of the holder and urged by a spring in the direction of the location of the lamp. This measure ensures a better contact between the movable contacts and the cap contacts, even if the holders are not accurately spaced apart or if the length of the lamp is slightly different from the normal length. In the present case, the term "axis of the holder" is to be understood to mean the axis about which the member is adapted to rotate. If the member has a little lateral clearance in the housing, it is at the same time ensured that the member can be turned even if the lamp occupies an oblique position in the holder. However, the rotatable member is preferably conical or spherical on the side facing the lamp, so that it is adapted to move like a ball-and-socket joint in the housing of the holder.

The contact surface between the fixed and the movable contacts is preferably at the periphery of the rotatable member, and the width of at least one of these contacts is such that the elec-

2

trical connection is independent of the movement of the member in the axial direction. In our co-pending applications Serial Nos. 177,262, 177,263, and 177,264 filed August 2, 1950, similar lamp-holder constructions are defined and different features thereof claimed.

In order that the invention may be readily carried into effect, one example will now be described in detail with reference to the accompanying drawings, in which:

Fig. 1 is a view of that side of the holder which is remote from the side where the lamp is introduced and which will be referred to as the rear side. In this figure, the rear wall of the holder and the rotatable member are broken away;

Fig. 2 is a sectional view taken on the line II—II of Fig. 1;

Fig. 3 is a sectional view taken on the line III—III of Figs. 1 and 2;

Fig. 4 is a view of the back of the movable member and

Figs. 5 and 6 are a sectional view and an end view respectively of a lamp cap for use with this holder.

Fig. 7 is a side view of the same lamp cap.

Fig. 8 is a side view of the holder as seen from a direction, opposite to that, from which Fig. 1 was viewed.

The holder comprises a casing 1 of insulating material, for example a moulding material. The bottom of the casing is provided with an aperture 2 through which one end of a lamp cap is adapted to pass from above (Figs. 1, 2, and 8), the lamp being moved parallel to itself. About the aperture 2 on the bottom 3 of the casing provision is made of an approximately horseshoe shaped edge 4 with its opening 5 upwards. This edge 4 (shown in broken lines in Fig. 2) constitutes a location for the movable member 6 which is urged into this location by a helical spring 7. At the back, the spring 7 rests on a plate 8 which is preferably also made of insulating material and constitutes the rear wall of the holder. At the top it is held under a hook-shaped part 9 of the box 1 and at the bottom by a flanged tube 10.

At the bottom end of the casing 1 an elevation 11 constitutes a location 12 for the bottom end of the fixed contact 13. This contact is shaped as a curved spring, the top end 14 of which engages the periphery of the movable member 6 and the bottom end of which has a hook-shaped part 15 which fits in the location 12. This part has an aperture through which passes 55 a screw 16 with a nut 17 which are housed be-

tween the casing 1 and the rear wall 8. The screw can be tightened through an aperture 18 in the casing, so that a conductor can be clamped between the nut 17 and the hook-shaped part 15.

The movable member 6 (Figs. 2 and 4) consists of a disc of insulating moulding material, the front of which is bevelled at the edge 19 so as to be conical, so that it is urged to the centre of the location of the edge 4 under the action of spring 7. However, it may also occupy an oblique position, if required by the position of the lamp relative to the holder. At the back the member 6 is provided with a cavity 20, in which fits spring 7. The front of this cavity has an elongated aperture 21 through which, from the rear side, two crescent-shaped contact plates 22 are introduced, which together form one contact. Each of these plates is integral with a strip 23 which extends along the rear surface of the member 6 and forms a contact 24 at the periphery thereof. The member 6 is provided at its periphery with four slots 25, two of which accommodate the strips 23. The plates 22 are held in the member by spring 7 through the intermediary of an insulating plate 26.

The lamp cap (see Figs. 5-7) to be used with these lampholders comprises a hood 27, the bottom of which has a circular aperture 28 with two elongated extensions 29. This aperture is shown in broken lines in Fig. 6.

A body 30 of insulating material with two lugs 31 is passed through these extensions and secured, after another insulating plate 32 has been provided within the hood, by means of a flanged tube 33 and a washer 34. In this flanged tube, a supply wire 35 for an electrode of the lamp is secured by soldering. The width of the aperture 28 is chosen to be such that sufficient insulation of the flanged tube 33 from the hood 27 is ensured.

Furthermore, the insulating body 30 has two ears 36 which are formed by splitting the part 27 of the body extending beyond the hood for the major part by a slit 37 (a side wall of which is shown in Fig. 5), and by providing a circular groove 38 in the projecting part adjoining the hood. The bottom of this groove has a circular periphery with two flattened portions (broken line in Fig. 6). The distance A between these flattened portions is slightly smaller than the width B of the aperture 5 of the holder (Fig. 6 and Fig. 1 respectively).

The operation of this holder will be described for one end of the lamp; at the other end a similar holder is to be imagined.

The holder is mounted with the member 6 occupying the position shown in Fig. 2. The contacts 22 cannot now be alive, since the end 14 of the fixed contact 13 does not engage one of the strips 23 (Fig. 4).

One lamp end is introduced from above into the holder and turned so that the body 30 passes through the aperture 5, the slit 37 being directed in a manner such that the contacts 22 slide into it and engage the conductor 35 by way of the flanged tube 33. If the lamp is turned one quarter stroke about the axis of the lamp, the ears 36 engage the contact plates 22, cause the member 6 to turn and one of the strips 23 engages the end 14 of the fixed contact 13. This contact may now be alive. At the same time removal of the lamp is prevented, since the insulating body 30 of the lamp cap is locked. Displacement of the lamp parallel to the axis is prevented both by the contacts 22 now occupying an oblique posi-

tion and by that part of the body which is provided with the circular slot 38 and can no longer pass through the aperture 5. Displacement of the lamp in the axial direction is impossible, since the ears 36 engage behind the edge of the aperture 2 provided in the bottom of the casing 1.

The safety of this holder is ensured, since it is not possible to remove the lamp from the holder without first switching off at the contacts 22.

10 It is possible, however, to introduce only one of the lamp ends into the holder and then to turn the lamp. The contact of the cap at the other lamp end may then be alive through the internal resistance of the lamp but, even should this occur, the slot 37 is so narrow and deep that this contact cannot be touched.

15 From Fig. 2 it will be seen that the member 6 has a great freedom of motion. Within limits, it is capable of conforming to the position of the lamp. In this construction of the holder, the fixed contact 13 has such a width that it is adapted to engage the contacts 24 both when the body 6 is completely urged into its location (as shown in Fig. 2) and when it is approximately urged against the rear wall 8.

20 The flexibility of this holder is promoted since the insulating body 30 of the lamp cap has a comparatively small sectional area. Therefore, it can be placed in the holder in a more oblique position, without the risk of jamming or rupture, than in the case of holders in which the insulating end has the same diameter as the lamp.

25 The lamp holder and cap shown in the drawings are unipolar. It will be obvious that by providing small alterations both of them may be made bipolar. The device is primarily intended for use with low-pressure mercury-vapour discharge tubes, so-called fluorescent tubes, but it may also be used for tubular incandescent lamps without the need for modifications.

30 What we claim is:

35 1. A lampholder for use with an elongated tubular lamp having a given longitudinal axis and a terminal cap at each end with a contact thereon, comprising a housing of insulating material defining an arcuate seat lying in a plane substantially perpendicular to said longitudinal axis, a fixed contact within the housing, a longitudinally-displaceable member rotatable within the housing and having an arcuate surface portion adapted to engage said seat, a contact on said rotatable member adapted to engage the terminal cap upon insertion of the latter into the housing, means operative upon rotation of said rotatable member to effect an electrical connection between the terminal contact and the fixed contact, and resilient means urging said rotatable member against said seat and against said terminal cap when the latter is inserted into the housing to insure positive contact and proper alignment of the rotatable member and the terminal contact.

40 2. A lampholder for use with an elongated tubular lamp having a given longitudinal axis and a terminal cap at each end with a contact thereon, comprising a housing of insulating material defining an arcuate seat lying in a plane substantially perpendicular to said longitudinal axis, a fixed contact within the housing, a longitudinally-displaceable and pivotable member rotatable within the housing and adapted to engage said seat, a contact on said rotatable member adapted to engage the terminal cap upon insertion of the latter into the housing, said rotatable

member having a spherical surface portion on the side thereof adjacent the terminal cap whereby said rotatable member is adapted to move within the housing in a manner similar to a ball and socket joint, means operative upon rotation of said rotatable member to effect an electrical connection between the terminal contact and the fixed contact, and resilient means urging said rotatable member against said seat and against said terminal cap when the latter is inserted into the housing to insure positive contact and proper alignment of the rotatable member and the terminal contact.

3. A lampholder for use with an elongated tubular lamp having a given longitudinal axis and a terminal cap at each end with a contact thereon, comprising a housing of insulating material defining an inwardly-facing arcuate seat lying in a plane substantially perpendicular to said longitudinal axis, a fixed contact within the housing, a longitudinally-displaceable and pivotable member rotatable within the housing and adapted to engage said seat, a contact on said rotatable member adapted to engage the terminal cap upon insertion of the latter into the housing, said rotatable member having a conical surface portion on the side thereof adjacent the terminal cap whereby said rotatable member is adapted to move within the housing in a manner similar to a ball and socket joint, means operative upon rotation of said rotatable member to effect an electrical connection between the terminal contact and the fixed contact, and resilient means urging said rotatable member against said seat and against said terminal cap when the latter is inserted into the housing to insure positive contact and proper

alignment of the rotatable member and the terminal contact.

4. A lampholder for use with an elongated tubular lamp having a given longitudinal axis and a terminal cap at each end with a contact thereon, comprising a housing of insulating material defining an arcuate seat lying in a plane substantially perpendicular to said longitudinal axis, a fixed contact of given dimensions within the housing, a longitudinally-displaceable and pivotable member rotatable within the housing and having an arcuate surface portion adapted to engage said seat, a contact on said rotatable member adapted to engage the terminal cap upon insertion of the latter into the housing, means operative upon rotation of said rotatable member to effect an electrical connection between the terminal contact and the fixed contact, and resilient means urging said rotatable member against said seat and against said terminal cap when the latter is inserted into the housing to insure positive contact and proper alignment of the rotatable member and the terminal contact, the dimensions of said fixed contact being such that positive contact between it and the contact on the rotatable member is assured independently of movement of the rotatable member in the longitudinal direction.
